Inventor:
Harry B. White,
By *H. S. DeMaree* Atty

UNITED STATES PATENT OFFICE

HARRY B. WHITE, OF CANTON, OHIO, ASSIGNOR TO THE HOOVER COMPANY, A CORPORATION OF OHIO

CLEANER

Application filed December 24, 1927. Serial No. 242,310.

Vacuum cleaners as now constructed are of three general types, the so-called straight-air cleaner, the brush cleaner, in which the brush is driven by some form of drive from one or more of the floor contacting wheels of the cleaner, and the type in which a brush or agitator member is rotated by some form of drive from the motor-shaft.

The invention disclosed in this application relates particularly to the third or last type above mentioned, that is, the type wherein a revolute brush or agitator member is driven from the cleaner motor.

The invention disclosed relates particularly to a new and improved device for mounting the revolute carpet contacting member, and the objects of the invention are to provide an improved support for the revolute floor contacting member of a suction cleaner, to provide such a mounting or support to securely hold the revolute member in its proper position and to provide such a construction wherein while the revolute member is securely held in its proper position, it may readily be removed without tools and with a minimum of effort.

Other and further objects of the invention such as the provision of a construction of simple design, low cost of manufacture, and other similar and like objects will be apparent from an inspection of the accompanying description and drawings.

In the drawings;

Figure 1 discloses a bottom plan view of a cleaner with the invention applied;

Fig. 2 is an end elevation of the forward part of the cleaner with a side wall broken away to show the details of the invention;

Fig. 3 is a perspective of the cam latch member detail; and

Fig. 4 is a perspective of one end of the mounting frame.

The invention comprises in general a U-shaped frame having an elongated base portion with short side portions or legs. These side portions or legs of the U-frame are pivoted to the end walls of the cleaner adjacent the nozzle opening and slightly to the rear thereof in order that the frame may

swing freely into and out of the nozzle opening.

The cleaner shown for the purpose of illustrating the invention and its application is one well known in the suction cleaner art, so that it is thought unnecessary to give any detailed description of the general arrangement. The description will be limited to the portion of the showing having to do specifically with the invention and such related parts as must necessarily be described in order that the relation of the parts may be understood.

The cleaner terminates forwardly in a substantially rectangular portion, a part of which comprises a downwardly opening nozzle inlet defined by front and rear nozzle lips 10 and 11 and by end walls 12 and 13 of the main casting. Suction passage 14 opens into the intake nozzle and a rotating agitator 15 is mounted in the suction nozzle, which agitator is mounted in an agitator frame 16. Agitator frame 16 is substantially U-shaped, having a relatively long base portion, which in this particular instance, comprises the forward lip 10 of the nozzle, and two relatively short side or arm portions 17.

The agitator mounting frame is pivoted to side walls 12 and 13 of the cleaner at 18. Pivot points 18, to the rear of nozzle lip 11, and slots at 19 are provided in order that the agitator mounting frame may freely swing into and out of the nozzle opening.

On the outside of side arm 17 of the frame, there is mounted a curved spring member 20 secured by means of a rivet 21. The spring 20 is of general semi-circular shape and has a portion 22 which is curved to lie in arcuate slot 23 and it is provided with an end portion 24 which is turned out at substantially right angles to the main body of the spring in order that the upturned end 24 may project slightly above the surface of frame arm 17, for a purpose to be later described.

On frame arm 17 there is provided a latch pivot 25 and a shaft receiving slot 26 is formed in said arm. At the bottom of side arm 17 there is an outturned tongue 27 which abuts main frame end wall 12 to properly position the frame with respect to the cleaner

nozzle when the frame is swung into normal operative position.

Mounted on latch pivot 25, there is a latch member 28 which is provided with a hole 29 to receive pivot 25. A further small opening or hole 30 is provided in latch member 28 to receive the upturned end 24 of spring 20. The latch is also provided with a small tongue 34 turned at substantial right angles to the general plane of the latch member and adapted to overlie the edge of the frame side member, and provide means whereby the latch may be readily operated. On the latch members there are provided two cam surfaces indicated at 31 and 32 respectively, of which cam surfaces 31 will be designated as a latching surface while surface 32 will be designated as a releasing surface.

The revoluble agitator 15 is provided with 20 trunnions or a central shaft on which it rotates, an end of such a shaft being shown in Figure 2 and indicated at 33.

Attention is now directed to several particular features of the invention which possibly would not normally appear to even one skilled in the art, unless they were particularly pointed out. Latching cam surface 31 is so designed that as latch 28 is swung about its pivot 25 there is a constant and gradually 30 increasing pressure brought to bear upon shaft end 33 to firmly seat it in its mounting in the bottom of slot 26, that is, the distance from a tangent to any point on this surface to the center of the latch pin is of a decreasing value from the outer or open end of the cam surface to its inner or closed end. Attention is also directed to releasing cam surface 32, which is so designed with respect to the pivot point of the latch 28 that as the 40 latch is swung into open position or counterclockwise, as viewed in Fig. 2, there is a positive tendency for this surface 32 to raise the shaft end 33 from its seat in the bottom of slot 26. In addition to these particular features just mentioned, attention is also directed to the fact that when latch member 28 is operated in a counterclockwise direction to the position in which shaft end 33 is free from its seat, that spring securing rivet 21, latch pivot 25 and the point of connection of the 50 spring to the latch member, or otherwise the upturned end 24 of the spring, fall substantially in line or even slightly past a line drawn through the rivet and the pivot, so that the latch when opened is in a stable position without tendency to spring to its closed position. With the latch in this stable position or just slightly past such aligned condition, a 60 very slight movement of the latch in a clockwise direction will throw spring end 24 slightly past the line through the rivet and pivot so that the spring and latch will no longer be in a stable condition and will tend to immediately spring shut and to be constantly urged 70 toward closed position by the action of spring

20. In addition to the fact that the latch may be closed by a very slight closing movement thereof, it may also be closed by a very slight pressure upon the agitator or revoluble member tending to force its shaft to its seat since the shaft will exert a pressure on releasing cam surface 32 which pressure, due to the relative relation of the cam surface and the latch pivot will cause the latch to move slightly toward closing position which will likewise throw the latch member and spring into an unstable condition to force the latch into its closed position.

It is believed that the above description fully and thoroughly describes an agitator mounting which is very easy and simple to operate and which fulfills the various and sundry objects of invention as particularly mentioned.

It is to be understood that while the majority of the details of construction have been described in the singular, the agitator mounting frame is provided with a side member at each end and that the construction of each end and its related parts is the same with the exception, of course, that one part is a right-hand part and the other part is a left-hand part.

I claim:—

1. In a suction cleaner having a downwardly opening intake nozzle, a U-shaped mounting frame, said mounting frame having a long base portion and short side members, the side members of the frame being pivotally mounted adjacent the intake nozzle, a revoluble agitator in the intake nozzle and having supports projecting from its ends, said side members being provided with seats for said supports, and a latch member pivotally mounted on each side member to secure said supports on their seats and each having two cam surfaces, one of said cam surfaces having a progressively decreasing effective radius in one direction of rotation of the latch member, and the other of said cam surfaces having an effective radius progressively increasing at a relatively high rate with respect to the other cam surface and effective in the opposite direction of rotation of the latch member.

2. A carrier for mounting an agitator of a suction cleaner comprising a U-shaped frame having a relatively long base portion and short side portions, said side portions being provided with seats for receiving projections extending axially of the agitator and latch members pivoted upon said side portions, each of said latch members having a cam face thereon for engaging one of said axial projections and of slightly progressively decreasing effective radius from the latch pivot when considered for one direction of rotation of the latch member for forcing said projection toward said seat.

3. In a suction cleaner having a down-

- wardly opening intake nozzle, a U-shaped mounting frame having a relatively long base portion and short side portions, means adjacent the intake nozzle for pivotally 5 mounting the frame side portions, a revoluble agitator in the intake nozzle, a shaft on which the agitator is revolubly supported and having end mounting projections, said frame side portions having seats thereon for 10 said mounting projections, a latch member pivotally mounted on each frame side portion and having a slot therein, the sides of said slot constituting opposed cam surfaces each having an increasing radius about the 15 latch pivot in one direction whereby upon motion of the latch member in one direction one of said cam surfaces will force the mounting projection toward its seat and upon motion of the latch member in the opposite 20 direction the other of said cam surfaces will force the mounting projection away from its seat, and a resilient member biasing the latch member in the first mentioned direction.
4. A suction cleaner having an intake nozzle and an agitator member in said nozzle, means for detachably mounting said agitator member comprising a plate having a slot therein and a seat, a shaft on which the agitator is revolubly mounted and having a portion 25 thereof adapted to slide in said slot, a latch member pivotally mounted on said plate and having opposed cam surfaces thereon for forcing said projection toward said seat and away from said seat respectively, means limiting the movement of said latch in each direction, and resilient means 30 effective on opposite sides of the pivot point of said latch to urge said latch toward projection seating position during the latter 35 part of its movement in one direction and toward projection unseating position during the latter part of its movement in the opposite direction.
5. The combination with a suction cleaner 40 having a downwardly extending intake nozzle, an agitator in said nozzle, a shaft revolubly supporting said agitator, and a frame carried by said cleaner and supporting said shaft, of a latch mounted on said frame adjacent 45 the end of said agitator and engaging the end of said shaft, and means for urging said latch toward one position to hold said shaft to said frame and toward another position to assist in withdrawing said shaft from said 50 frame.
6. A suction cleaner having an intake nozzle, an agitator in said nozzle, means revolubly supporting said agitator and comprising a projection extending axially of said agitator, a plate having a slot therein to receive 55 said projection and having a seat at the end of said slot, a latch member carried by said plate, and means tending to move said latch member from an intermediate position toward end positions, said latch member having a cam surface thereon engageable with said projection to retain it within said slot.
7. A suction cleaner casing having an intake nozzle, an agitator in said nozzle, means revolubly supporting said agitator and comprising a projection extending axially of said agitator, means carried by said casing for guiding said projection and having a seat for engagement by said projection, a latch member pivotally carried by said casing, and means tending to swing said latch member from an intermediate position toward end positions, said latch member having thereon a portion for holding said projection against said seat and having a cam surface for forcing said projection away from its seat upon movement of said latch member in one direction and engageable by said projection to effect movement of said latch member past its intermediate position.
8. A suction cleaner casing having an intake nozzle, a device adapted to be mounted in said nozzle, and means for detachably securing said device to said casing comprising a projection extending endwise from said device, means carried by said casing for guiding said projection and having a seat for engagement by said projection, a latch member pivotally carried by said casing, and means tending to swing said latch member from an intermediate position toward end positions, said latch member having a portion for holding said projection against its seat and having a cam surface thereon engageable by said projection to throw said latch member past its intermediate position.
9. A suction cleaner casing having an intake nozzle, a device adapted to be mounted in said nozzle, and means for detachably securing said device to said casing comprising a projection extending endwise from said device, means carried by said casing for guiding said projection and having a seat for engagement by said projection, a latch member pivotally carried by said casing and having an arcuate slot therein to receive said projection and of a width greater than the corresponding dimension of said projection to provide lost motion, and resilient means tending to swing said latch member to secure said projection within said slot.

Signed at North Canton, in the county of Stark, and State of Ohio, this 17th day of December, A. D., 1927.
